UNITED STATES PATENT OFFICE.

WILLIAM O. GIRTON, OF SERENO, PENNSYLVANIA.

DESIGN FOR A BUNDLE-TIE.

SPECIFICATION forming part of Design No. 27,140, dated June 1, 1897.

Application filed April 15, 1897. Serial No. 632,321. Term of patent 14 years.

To all whom it may concern:

Be it known that I, WILLIAM O. GIRTON, a citizen of the United States, residing at Sereno, in the county of Columbia and State of Pennsylvania, have invented a new and original Design for a Bundle Tie or Fastener, of which the following is a specification.

This invention relates to a new and original design for a bundle tie or fastener; and it has for its object to provide a design of this character that shall be both useful and ornamental.

The leading feature of the design resides in a tie or fastener having a single-length wire body formed with an intermediate segmental arched portion, at one end of which arched portion one terminal of the body is bent to an approximate **S**-shape form, which **S**-shaped terminal is disposed at an acute angle to the chord of the intermediate arched portion, the opposite terminal of the body being folded into a straight **V**-shaped portion, also disposed at an acute angle to the chord of the arched portion.

In the drawings, Figure 1 is a perspective view of a tie or fastener embodying the here-

in-described design. Fig. 2 is a side view thereof. Fig. 3 is a plan view.

Referring to the drawings, the numeral 1 designates the intermediate segmental arched portion of the wire body forming the tie or fastener, and at one end of this arched portion 1 one terminal of the body (designated by the numeral 2) is bent to an approximate **S**-shaped form and is disposed at an acute angle to the chord of the segment 1. The terminal of the wire body opposite the **S**-shaped terminal 2 is folded into a straight **V**-shaped portion 3, which **V**-shaped portion 3 is also disposed at an acute angle to the chord of the segment or arched portion 1 and is provided with a laterally-deflected extremity 4.

What is claimed is—

The design for a bundle tie or fastener herein shown and described.

In testimony that I claim the foregoing as my own I have hereto affixed my signature in the presence of two witnesses.

WILLIAM O. GIRTON.
